United States Patent Office

Des. 203,106
Patented Dec. 7, 1965

203,106

AUTOMOBILE

Friedrich Geiger, Boblingen, and Karl Wilfert, Gerlinger-Waldstadt, Germany, assignors to Daimler-Benz Aktiengesellschaft, Stuttgart-Unterturkheim, Germany

Filed Mar. 2, 1964, Ser. No. 78,838

Claims priority, application Germany Sept. 4, 1963

Term of patent 14 years

(Cl. D14—3)

FIG. 3

FIG. 4

FIG. 5

FIGURE 1 is a perspective view of the automobile embodying my new design;

FIGURE 2 is a side view thereof;

FIGURE 3 is a top plan view thereof;

FIGURE 4 is a front elevational view thereof; and

FIGURE 5 is a rear elevational view thereof.

The dominant features of my design reside in the portions shown in full lines.

I claim:

The ornamental design for an automobile, substantially as shown and described.
